KNUT BERGLOF, OF BUFFALO, NEW YORK.

IGNITER.

Application filed August 3, 1921. Serial No. 489,502.

To all whom it may concern:

Be it known that I, KNUT BERGLOF, a subject of the King of Sweden, and resident of Buffalo, in the county of Erie and State of New York, have invented a certain new and useful Improvement in Igniters, of which the following is a specification.

This invention relates to improvements in igniters particularly of the type intended for use in connection with internal combustion engines for firing the charge in the cylinder.

In an igniter embodying this invention there is provided a chamber to which gas under compression is supplied from the cylinder of the engine. The gas in the chamber is suddenly placed under high compression so that it ignites spontaneously and the burning gas is then allowed to escape and fire the charge in the cylinder.

One object of this invention is to provide an igniter having a chamber in which a gas is spontaneously ignited by reason of high compression and which igniter is provided with means for controlling the time of ignition and with means for completely clearing the chamber from the spent gases.

Another object is to provide in the chamber of the igniter normally covered openings which are uncovered when the spontaneous ignition takes place to allow the burning gas to fire the charge in the cylinder.

A further object is to provide in this igniter means supplementing the action of gravity for insuring the proper co-action of the various parts and particularly for insuring the return of these parts to their proper relative positions after each operation.

Other objects will appear from a consideration of the specifications and drawing which form a part thereof and in which;

Figure 1 shows one embodiment of the invention mounted upon a cylinder of an internal combustion engine;

Figure 2, 3, 4, 5 and 6 show the various positions assumed by the parts of the igniter during its operation;

Figure 7 is a sectional view taken on the line 7—7 of Figure 3, illustrating the timing mechanism;

Figure 8 is a cross section on the line 8—8 of Figure 4; and

Figure 9 is a cross section taken on the line 9—9 of Figure 5.

Referring to the drawings, the reference

numeral 10 is used to designate the upper portion of a cylinder of an internal combustion engine. The cylinder 10 has at its upper end a threaded opening 11 in which is mounted the lower end of the igniter A embodying one form of this invention. The igniter A consists of a tube 12 externally threaded at both ends; the upper end of the tube 12 being closed by a flanged cup 13 and the lower end by a member 14. In the cup 13 are provided holes 131 by which the upper part of the igniter is in communication with the outer air and the elements in said part are directly subjected to atmospheric pressure. The member 14 consists of an externally threaded tip 15 which engages the opening 11 in the cylinder and an internally threaded annular flange 16, which engages the tube 12. Intermediate the tip 15 and the flange 16 is a cup like portion 17 which is connected to the other portions by flat annular seats 18 and 19. In the cup portion 17 is a lining 20 having an annular flange 21 which rests upon the seat 18 and against which the lower end of the tube 12 bears so as to insure an absolute air tight joint.

Within the tube 12 is mounted a piston 22 provided with piston rings 23 and having annular flanges 24 and 25 forming a pocket in which rests the lower end of a spring 26 the upper end of which bears against the cap 13. The spring 26 thus functions to hold the piston 22 with its lower face bearing upon the flange 21 of the lining 20. Mounted to extend through a concentric hole 27 in the piston and surrounded by the annular flange 25 is a chamber 28 the walls of which are formed by a tube 29. Adjacent to its lower end the tube 29 is provided with an annular projection 30 which bears against the lower face of the piston 22 and which, when the chamber is raised, causes the piston to be raised also.

In a circumferential groove 31 adjacent to the upper end of the tube 29 is seated a ring 32 made up of two semi-circular members. Against this ring normally rests a sleeve 33 which surrounds the tube 29 and which is provided with a flat annular flange 34, the sleeve 33 being slightly recessed in order to receive the ring 32. Between the flange 34 of the sleeve 33 and the upper face of the piston 22 there is mounted a spring 35 which holds the sleeve 33 at all times in contact with the ring 32. It will thus be noted

- that while the piston 22 will be raised by the projection 30 if the chamber 28 is raised, the chamber also be raised if pressure be applied to the lower face of the piston.
- 5 Hence, except for the slight reciprocation against the force of the spring 35 permitted by the separation of the flange 25 and the sleeve 33, the piston and chamber will move as a unit.
- 10 At the lower end of the tube 29 is provided an inwardly projecting annular flange 36 which supports a conical valve seat 37. Resting on the seat 37 is a conical valve 38 through the stem 39 of which a cotter pin or 15 other suitable means 40 is inserted. This pin 40 will engage the under side of the valve seat 38 on the flange 36 as soon as the valve reaches its upward limit of reciprocation.
- 20 Mounted to reciprocate within the tube 29 and formed to rest upon the face of the valve 39 is a piston 41 provided with piston rings 42. The piston 41 has a concentric pocket 43 in which rests the lower end of a 25 spring 44, the upper end of which bears against the boss 45 on the under side of the cap 13. A rod or pin 46 projecting downwardly from the center of the boss extends partly through the coils of the spring 44 30 and prevents it from tilting. The upper edge of the piston 41 is provided with a thickened annular flange 47, which strikes against the boss 45 when the piston is at its upper limit of reciprocation. (See Fig. 2).
- 35 Mounted in the cuplike portion 17 of the lower member 14 is an annular check valve 48, the lower face of which is concaved thus providing an annular space 49 between the valve and the seat 19. This space is connected by the passage 50 through the tip 15 with the engine cylinder. The check valve 48 engages the lower end of the tube 29 which extends into a concentric hole 51 through the valve.
- 45 Above the valve 48 and between the lower end of the tube 29 and the inner face of the bearing 20 is provided a space 52 from which an annular opening 53 leads to the lower face of the piston 22. Through 50 the wall of the portion 17 and its lining 20 are provided slots 54 so that the space 52 is in direct communication with the outer air. The space 52 is ordinarily filled with spent gas from the preceding explosion as will appear from the description of 55 operation hereinbelow. As the valve 48 moves from the inoperative position shown in Fig. 1 to the operative position shown in Fig. 2 much of the gas in the space 52 will escape through the slots 54. The gas that does not so escape is trapped by the valve in the opening 53 and fills the space 55 between the lower face of the piston 22 and the seat 18. Since the valve 60 65 48 prevents any more gas or air from en-

tering the space 55 it of course follows that as the volume of the space is increased the gas becomes more rarefied so that a partial vacuum is created which increases as the piston 22 rises.

70 Through the tube 29 just above the projection 30 is provided a circle of holes 56 which are normally covered by the piston 22 but which are uncovered when the parts assume the positions shown in Figs. 5 and 6. The purpose of these holes will be disclosed in the description of operation.

75 Mounted to rotate around the cup like portion 17 of the member 14 is a sleeve or ring 57 having circumferential slots 58 which are of the same size as and which coincide with the slots 54 when the ring 57 is shifted by the handles 59. The effective size of the slots 54 can be adjusted as desired.

80 The operation of this igniter is controlled solely by the compressed gas in the cylinder 10 which through the passages 50 and 51 and the space 49 acts against the various valves and pistons to raise them 90 against the force of gravity and the tension of the springs 26, 35 and 44.

85 During the suction and exhaust strokes of the cylinder piston (not shown) the various parts retain the position shown in Figure 1. As soon, however, as the compression stroke starts the compressed gas in the cylinder passes through the openings 50 and 51 and raises the valve 38. The gas then rushes past the valve and bearing against the lower face of the piston 41 quickly raises it to the position shown in Figure 2, the spring 44 being too light to resist the pressure exerted by the compressed gas. The chamber 28 is thus 100 filled with the compressed gas from the cylinder 10. Simultaneously with this operation of the valve 38 the compressed gas fills the space 49 and raises the valve 48 so as to completely fill the space 52 and 105 prevent the entry of gas or air into the space 55.

110 As the cylinder piston rises and the pressure of the compressed gas in the cylinder increases, greater pressure is exerted 115 against the lower end of the flange 36 of the tube 29. Inasmuch as the piston 22 is held by the spring 26 against the flange 30 the pressure exerted by the compressed gas is resisted by the spring 26 and the 120 normal atmospheric pressure as will be disclosed from examination of Figs. 2 and 3. Since air can not enter the space 55, as the size of the space increases by the raising of the piston 22 the partial vacuum therein will increase and hence the effectiveness of the atmospheric pressure on the upper face of the piston 22 and against the pressure of the compressed gas also increases. 125 In connection with these forces, it will be 130

noted that the atmospheric pressure is exerted against the sectional area of the piston 22 as well as that of the tube 29 and that the compressed gas bears on both sides 5 of the flange 36 equally so that the compressed gas bears merely against the sectional area of the tube and consequently raises it. The piston 41 being at the upward limit of its reciprocation, and the 10 tube 29 raised by the compressed gas, the volume of the chamber 28 will diminish be evident from an examination of Figures 2 and 3 of the drawing.

The pressure of the compressed gas increases as the compression stroke of the cylinder piston in the cylinder continues until finally the tube 29 is forced out of the opening 51 in the valve 48. The gas then rushes in to fill the space 55 and since it 20 now exerts pressure against the sectional area of the piston 22 as well as of the tube 29 the parts are quickly forced into the position shown in Figure 4. During this movement of parts the valve 37 closes, the 25 valve being retarded by gravity and held against the seat by the increased pressure applied upon the gas in the chamber 28.

When the position shown in Figure 4 has been reached the pressure on the contained 30 gas in the chamber 28 is so great that it ignites spontaneously. This action in the chamber 28 further increases the pressure and forces the tube 29 downwardly through the piston 22 against the action of the spring 35 until the sleeve 33 bears upon the top of the annular flange 35. This exposes the openings 56 through which the burning gas thus escapes and fires the compressed gas in the cylinder 10 which fill the unobstructed 40 lower portion 55 of the igniter. The resultant explosion further increases the pressure against the under side of the piston 22 and the tube 29 and forces these parts to assume the position shown in Figure 6 in 45 which the piston 41 bears directly upon the upper face of the conical valve 38 and thus insures the complete scavenging of the chamber through the openings 56. When the exhaust stroke of the cylinder piston begins the parts of the igniter under the 50 force of gravity assisted by the springs 27, 35 and 44 assume the position shown in Figure 1 ready for further operation, most of the spent gas in the space 55 escaping through the slots 54 but part will remain in the space 52.

As pointed out above the effectiveness of the resistance to the pressure of the compressed gas in the cylinder of the atmospheric pressure on the piston 22 varies according to the partial vacuum created in the space 55.

The effectiveness varies directly with the intensity of the partial vacuum in the space 65 55 and consequently varies inversely with

the amount of gas or air trapped in the space 55. For example, if the ring 57 be turned so that the slots 54 are wide open a large part of the gas and air in the space 52 will escape when the valve 48 is raised 70 and only a small part be trapped in the space 55 so that a very high partial vacuum will be created by the raising of the piston 22 and as a result the resistance to the urge of the compressed gas in the cylinder to raise the chamber 28 will be great, and the chamber will not be freed from the valve 48 until the cylinder piston has completed or nearly completed its upward travel. If on the other hand the ring 57 be shifted 80 to close the slots 54 all the gas and air in the space 52 will be forced by the valve 48 through the passage 53 into the space 55 so that the intensity of the partial vacuum created by the piston 22 will be less than 85 before and as a result the resistance to the raising of the chamber by the compressed gas in the cylinder will be less so that the charge will be fired before the cylinder piston has completed its upward travel. In the 90 first example the time has been retarded while in the second example it has been advanced. It is obviously possible by shifting the ring 57 and adjusting the effective size of the slots 54 to regulate the time at 95 which the explosion in the engine cylinder will take place. Such regulation is absolutely essential for efficient operation of the engine.

It will be noted that an igniter made according to this invention can be regulated in the same way as the well known spark plug without the necessity of electric wiring, battery, or magneto, or timer.

While one embodiment only of this invention has been shown and described applicant is not to be limited thereby since it is obvious that others can be made without departing from the spirit and scope of the invention as set forth in the following 105 claims.

Having thus described my invention that which I claim as new and for which I desire the protection of Letters Patent of the United States is the following:

1. In an igniter for compressed gas in the cylinder of an internal combustion engine, a chamber adapted to be filled with such gas, means for compressing the gas in such chamber, a piston adapted to be raised by the compressed gas in the cylinder means co-operating with the piston to provide a chamber below the same and means for sealing said last named chamber during the raising of the piston, thereby to create a vacuum condition by which the raising of the piston is opposed.

2. In an igniter for compressed gas in the cylinder of an internal combustion engine, a chamber adapted to be filled with such gas,

means for compressing the gas in such chamber, a piston adapted to be raised by the compressed gas in the cylinder, means co-operating with the piston to provide a chamber 5 below the same and means effective during the raising of the piston for sealing said last named chamber.

3. In an igniter for compressed gas in the cylinder of an internal combustion engine, a 10 chamber adapted to be filled with such gas, means for compressing the gas in such chamber, a piston adapted to be raised by the compressed gas in the cylinder, means co-operating with the piston to provide a chamber below the same, and means actuated by the compressed gas in the cylinder for sealing said last named chamber.

4. In an igniter for compressed gas in the cylinder of an internal combustion engine, a 20 chamber adapted to be filled with such gas, means for compressing the gas in such chamber, a piston adapted to be raised by the compressed gas in the cylinder, means co-operating with the piston to provide a chamber below the same, and a valve below 25 said piston actuated by the compressed gas in the cylinder for sealing said last named chamber.

5. In an igniter for compressed gas in the 30 cylinder of an internal combustion engine, a piston, a cylinder therefor, means co-operating with said piston and cylinder to provide a chamber below said piston, said chamber having an opening, and a valve for closing 35 said opening, said valve being actuated by the compressed gas in the cylinder.

6. In an igniter for compressed gas in the 40 cylinder of an internal combustion engine, a piston, a cylinder therefor, means co-operating with said piston and cylinder to provide a chamber below said piston, said chamber having an opening, and a valve for sealing 45 said opening and preventing the escape of the gas from below the piston, said valve being actuated by the compressed gas in the cylinder.

7. In an igniter for compressed gas in the 50 cylinder of an internal combustion engine, a piston, a cylinder therefor, means co-operating with said piston and cylinder to provide a chamber below said piston, said chamber having an opening, a valve for sealing 55 said opening and preventing the escape of the gas from below the piston, said valve being actuated by the compressed gas in the cylinder, and means for raising said piston.

8. In an igniter for compressed gas in the 60 cylinder of an internal combustion engine, a part providing a chamber adapted to be filled with such gas, and an annular piston surrounding said part, said part being raised by compressed gas in the cylinder and having means to engage said piston and raise the same and means whereby said piston opposes the raising of said part.

9. In an igniter for compressed gas in the cylinder of an internal combustion engine, a part providing a chamber adapted to be filled with such gas, and an annular piston surrounding said part, said part being raised 70 by the compressed gas in the cylinder and having means to engage said piston and raise the same and means effective only during an initial period of the raising of said part whereby said piston opposes the raising of 75 said part.

10. In an igniter for compressed gas in the cylinder of an internal combustion engine, a part providing a chamber adapted to be filled with such gas, a piston surrounding 80 said part, means for insuring the substantially simultaneous reciprocation of said part and piston, and means whereby said piston is raised by the compressed gas in the cylinder acting first against the chamber alone 85 and later against both chamber and piston.

11. In an igniter for compressed gas in the cylinder of an internal combustion engine, a part providing a chamber adapted to be filled with such gas, a piston surrounding 90 said part, means for insuring the substantially simultaneous reciprocation of said part and piston, and a valve below the piston and surrounding the lower end of the part, said valve being raised by the compressed gas in 95 the cylinder and said piston and part being raised by such gas acting first against the part alone and later against both part and piston.

12. In an igniter for compressed gas in the cylinder of an internal combustion engine, a part providing a chamber adapted to be filled with such gas, a piston in said chamber, said chamber having openings near its lower end, an annular piston surrounding 105 said part, and normally covering said openings, said annular piston and part being raised, relative to the piston in the chamber, by the compressed gas in the cylinder until the gas in the chamber is so compressed that 110 it ignites spontaneously, the result of that ignition being to depress the part relative to the annular piston and thereby uncover the openings in the chamber to permit the burning gas to escape and explode the compressed gas in the cylinder; the annular piston and part being further raised by the force of the explosion so that the chamber is completely 115 filled by the first named piston.

13. In an igniter for compressed gas in the cylinder of an internal combustion engine, a chamber adapted to be filled with such gas, means for compressing such gas until it ignites spontaneously, means providing a vacuum influence to which the compressing 120 means is subject and means for timing the operation by regulating the intensity of the vacuum influence.

14. In an igniter for compressed gas in the cylinder of an internal combustion engine, a 130

chamber adapted to be filled with such gas, an annular piston surrounding said chamber, the lower face of said piston when inoperative being in communication through a passage with the outer air and means for adjusting the size of said passage for regulating the time of operation of said igniter.

15. In an igniter for compressed gas in the cylinder of an internal combustion engine, a chamber adapted to be filled with such gas, means including an annular piston for compressing the gas in the chamber until it ignites spontaneously, an annular seat against which said piston bears at its lowest limit of reciprocation, said seat having an opening therethrough, a valve in said igniter below said seat, said igniter having a chamber between said valve and said seat and the wall of said chamber having slots communicating with the outer air, and means for regulating the effective size of said slots.

16. In an igniter for compressed gas in the cylinder of an internal combustion engine, a chamber adapted to be filled with such gas, means including an annular piston for compressing the gas in the chamber until it ignites spontaneously, an annular seat against which said piston bears at its lowest limit of reciprocation, said seat having an opening therethrough, a valve in said igniter below said seat, said igniter having a chamber between said valve and said seat and the wall of said chamber having slots communicating with the outer air, and means for regulating the effective size of said slots.

17. In an igniter for compressed gas in the cylinder of an internal combustion engine, a chamber adapted to be filled with such gas, means including an annular piston for compressing the gas in the chamber until it ignites spontaneously, an annular seat

against which said piston bears at its lowest limit of reciprocation, said seat having an opening therethrough, a valve in said igniter below said seat, said igniter having a chamber between said valve and said seat and the wall of said chamber having slots communicating with the outer air, and a ring on said igniter having slots coinciding in one position of the ring with the slots first named.

18. In an igniter for compressed gas in the cylinder of an internal combustion engine, a chamber adapted to be filled with such gas, means including an annular piston for compressing the gas in the chamber until it ignites spontaneously, an annular seat against which said piston bears at its lowest limit of reciprocation, said seat having an opening therethrough, a valve in said igniter below said seat, said igniter having a chamber between said valve and said seat and the wall of said chamber having slots communicating with the outer air, and a ring on said igniter having slots coinciding in one position of the ring with the slots first named.

19. In an igniter for compressed gas in the cylinder of an internal combustion engine, a chamber in which such gas from said cylinder is compressed until it ignites spontaneously, said compression being the result of the action of the compressed gas in said cylinder upon said chamber, an annular piston surrounding said chamber, a valve below said piston and also surrounding said chamber, said valve preventing the compressed gas in the cylinder from bearing directly upon said piston until said chamber is raised out of contact with said valve.

In testimony whereof, I affix my signature.

KNUT BERGLOF.
